Specification for Design.

Patented Feb. 9, 1915.

Application filed October 24, 1914. Serial No. 868,536. Term of patent 3½ years.

To all whom it may concern:

Be it known that I, SHERRY GOLDBERG, a citizen of the United States, residing in the borough of Bronx, city and county of New York, and State of New York, have invented a new, original, and ornamental Design for a Button-Face, of which the following is a specification, reference being had to the accompanying drawing, forming part thereof, wherein—elevation of the button illustrated in Fig. 1 to illustrate further the face of the button; in this view, the lower portion or back of the button is indicated in dotted outline.

I claim:

The ornamental design for a button face, as shown.

SHERRY GOLDBERG.
